LINK MECHANISM FOR CIRCUIT BREAKERS.

Application filed June 4, 1926, Serial No. 113,639, and in Sweden June 19, 1925.

In circuit-breakers, which are enclosed in a tank containing a cooling medium, for instance oil, and which are operated by means of a shaft projecting through the wall of the tank, it is of a certain importance to enable the movable contact members to be moved through a large distance by a comparatively small rotation of the shaft. The present invention has for its object to provide a link mechanism for circuit-breakers permitting such an operation.

A form of the invention is illustrated in the accompanying drawing, where Fig. 1 shows a circuit-breaker with the link mechanism in a front view and the tank in section, while Fig. 2 shows a simplified geometrical view of the link system in three different positions.

In the tank 1 are two stationary contacts 2, 2 adapted to be connected by a vertically movable bridge contact 3. The latter is guided by one or more rods 4 and is operated by means of a crank and pitman mechanism, consisting of a link 5 and an arm 6 fixed on a shaft 7. When the breaker is moved from closed to open position or vice versa, this shaft should be rotated about one half turn for effecting the largest possible movement of the bridge piece 3.

The breaker is operated by means of a shaft 8 projecting through the wall of the tank. For certain reasons, for instance, in order to provide a simple operation of several poles of the breaker by means of a draw-bar, it may be desirable to rotate the said shaft 8 only a quarter of a turn for effecting the closing or breaking operation. For transmitting the motion from shaft 8 to shaft 7 and simultaneously doubling the angle of rotation, there is used one arm 10 mounted on the former and one arm 9 mounted on the latter and a link 11 connecting both arms. The arm 10 should be considerably longer than—for instance about twice as long as—the arm 9, and the length of the link 11 should lie between those of the two arms. The aspect of the link system in three different positions is diagrammatically shown in Fig. 2, viz in full-drawn lines in one extreme position (corresponding to

closed contacts), in dash lines in an intermediary position and in dotted lines in the other extreme position (corresponding to open contacts). It is evident from Fig. 2, that the arm 9 is rotated one half turn as 55 the arm 10 is rotated a quarter of a turn.

For giving appropriate angles between the arms and link in different positions the center of the shaft 8 should lie approximately in the extension of the arm 9 when the latter occupies its middle position, but rather large deviations from this rule are possible without appreciably interfering with the operation of the mechanism. The arms and link may of course be curved, as 60 shown in Fig. 1, if this is found necessary for providing space for other members of the mechanism.

We claim as our invention:

1. In a circuit breaker having a fixed 70 and a movable contact, an operating shaft adapted to turn through approximately 90°, an operated shaft mounted adjacent and parallel to the operating shaft and adapted to turn through approximately 180°, an arm 75 secured on the operating shaft, a relatively short arm secured on the operated shaft a link connecting said arms for transmitting turning movement from the operating to the operated shaft—the operating shaft being 80 so disposed relatively to the path of movement of the said short arm that the latter may be swung freely through 180° by the said link without bringing the ends of the link and the operated shaft into locking or 85 dead-center positions—, and connecting means between the operated shaft and the movable contact whereby rotation of the said shaft actuates the movable contact.

2. A circuit-breaker enclosed in a tank 90 containing a cooling medium, and comprising an operating shaft projecting through the wall of said tank and adapted to turn through approximately 90°, a second shaft mounted in the tank parallel to the first 95 shaft, an arm fixed on the latter shaft, a link slightly longer than the arm and connected thereto, a second arm about twice the length of the first one connected to said link and fixed on the first-mentioned shaft 100.

which is situated approximately in the extension of said first arm when the latter occupies a position half way between its two extreme positions—so that the first-mentioned arm may be swung freely through approximately 180° by the said link without bringing the ends of the link and the said second shaft into a locking or dead-center position—, and crank mechanism connecting said second shaft to a movable contact 10 of the circuit-breaker.

In testimony whereof we have signed our names to this specification.

DANIEL RÖNNBERG.
ADOLF ROOTH.
